(57) **CLAIM**

The ornamental design for a casement window operator handle and cover, as shown and described.

DESCRIPTION

FIG. 1 is a perspective view of a casement window operator handle and cover showing our new design, shown in its environmental use;

FIG. 2 is a front elevation view of the casement window operator handle and cover depicted in FIG. 1;

FIG. 3 is a top plan view of the casement window operator handle and cover depicted in FIG. 1;

FIG. 4 is a bottom plan view of the casement window operator handle and cover depicted in FIG. 1;

FIG. 5 is a rear elevation view of the casement window operator handle and cover depicted in FIG. 1;

FIG. 6 is a side elevation view of the P casement window operator handle and cover depicted in FIG. 1; and,

FIG. 7 is an opposing side elevation view of the casement window operator handle and cover depicted in FIG. 1.

The broken lines are included for the purpose of illustration and form no part of the claimed design.
